UNITED STATES PATENT OFFICE.

JOHN EDWD. MELLOR, OF NEW YORK, N. Y.

SPRING-HINGE.

SPECIFICATION forming part of Letters Patent No. 631,805, dated August 29, 1899.

Application filed May 29, 1897. Serial No. 638,678. (No model.)

To all whom it may concern:

Be it known that I, JOHN EDWD. MELLOR, a subject of the Queen of Great Britain, and a resident of the city of New York, in the county of New York and State of New York, have invented certain new and useful Improvements in Spring-Hinges, of which the following is a specification.

This invention relates to improvements in spring-hinges which are used for automatically closing a door.

The object of my invention is to provide a new and improved spring of that kind which is simple in construction, strong and durable, and can be applied on doors opening in one direction only or on doors opening in both directions.

In the accompanying drawings, forming a part of this specification, and in which like letters of reference indicate like parts in all the views, Figure 1 is an elevation of the upper inner corner of a door provided with one construction of my improved door-spring. Fig. 2 is an enlarged vertical longitudinal sectional view through the spring and its casing. Fig. 3 is a plan view of the construction shown in Fig. 2, the cover being removed. Fig. 4 is an elevation of the upper inner corner of a door with another construction of my improved spring. Fig. 5 is an enlarged vertical longitudinal sectional elevation through the spring and casing shown in Fig. 4. Fig. 6 is a perspective view of the slotted sleeve around which the leaf-spring is wound.

Figs. 1, 2, and 3 show the construction of spring used for doors opening in both directions. The upper inner corner of the door A is cut out rectangularly, and in the same a right-angled strip B is fastened, from which the pivot-pin B', fixed on said strip, projects upward. A spring-drum C, having central openings in its bottom C', top C², and intermediate horizontal partition C³ for receiving the pin B', is provided with wings C⁴, by means of which it can be fastened to the door-casing D. The drum C has a longitudinal interior groove E extending from the top to bottom. Two leaf-springs F' and F², coiled in opposite directions, are placed into the casing C and are separated from each other by the horizontal partition C³, as shown, and each

spring is provided at its outer end with a pin F, located loosely within the groove E. The pivot-pin B' is surrounded loosely by two sleeves G—one within each spring F' and F²—55 and each sleeve is provided with a vertical slot a, extending from top to bottom, and a horizontal slot b, extending from the slot a around each side to a web d, separating the inner ends of the slot b at a point diametrically opposite the slot a, and each sleeve also has a lug g on the bottom edge and diametrically opposite the slot a, which lugs g engage the stop-lugs h' and h² on the upper surface of the bottom C' of the drum C and the upper surface of the partition C³, respectively. 60

The pin B' has two studs H' H², which enter the horizontal slots b of the sleeves G, and each leaf-spring F' has an inwardly-projecting pin J, which also enters the horizontal slots 70 b of the sleeves G. When the door A is swung in the direction of the arrow X', the pivot-pin B' turns with it, and as the stud H² bears against one side of the web d the upper sleeve G is turned with the pivot-pin B', and as the other edge of the web d bears against the pin J on the inner end of the upper spring F² the spring is tightened and brought into greater tension, so that when the door is released it is swung back in the inverse direction of the arrow X' under the action of the expanding-spring F². The upper sleeve G can turn with the pivot-pin B' when the door is swung in the direction of the arrow X', as the lug g of the upper sleeve G is on that side of the stop-lug h² on the partition C³ toward which the door moves when swung in the direction of the arrow X'. The studs H' and H² on the pivot-pin B' engage the web d of the respective sleeves G on opposing sides thereof, and 80 since these studs travel freely in the slots b of said sleeves it follows that when the door is swinging in one direction, as in the direction indicated by arrow x', the stud H² is brought into active engagement with the upper sleeve G, thus winding the spring F², while the stud H', being on the opposite side of the web d of the lower sleeve G, moves freely in the slot b away therefrom, and thus the spring F' remains inactive until the spring 85 F² returns the door to its normal position, when upon the movement of the door the

spring F' is brought into action and spring F² remains inactive. Thus when the door is forcibly opened in one direction the upper spring is tightened and the lower one is not affected, and vice versa. When the door is forcibly opened in the opposite direction, the lower spring is tightened and the upper one is not affected. When the door is closed by either spring, the spring can only act until the lug g of the corresponding sleeve G comes in contact with the stop-lug h' or h³, respectively.

In the construction shown in Figs. 4 and 5, which is for a door opening in one direction only—that is, in the direction from the face of the drawings—the drum C is fixed to the outside of the door-casing D', and the pin B² is held by a set-screw M on a bracket-piece N, attached to the door A'. When this set-screw is loosened, the spring does not come into action; but where the set-screw is tightened the pivot-pin is locked to the door, and the spring can act when the door is opened. The operation is the same as the operation of one of the springs previously described. The pin B' or B² forms the upper pivot for the door, and at the bottom of the door any pivot of suitable construction and arrangement is provided. The partition C³ has a wing O located in the groove E to prevent said partition from turning.

Having thus described my invention, what I claim as new, and desire to secure by Letters Patent, is—

1. In a spring-hinge, the combination with a sleeve having a vertical slot open at its ends and a horizontal slot, extending in opposite directions from the vertical slot, of a pin loosely fitting in said sleeve, a projecting lug on the pin and adapted to pass into the slots in the sleeve, a casing or drum in which the pin is seated, a spring in said casing and sleeve, and means for operatively con-

necting said sleeve and casing, substantially as herein shown and described. 45

2. In a spring-hinge, the combination with a pivot-pin to be secured on the door, of a spring-drum to be secured to the door-casing, a stud on the pivot-pin, a sleeve mounted loosely on the pivot-pin, which sleeve has a horizontal slot in which the stud on the pivot-pin is located, a leaf-spring loosely surrounding the sleeve, a pin on the inner end of said spring and within the horizontal slot in the sleeve, substantially as herein shown and described. 50

3. In a spring-hinge, the combination with a pivot-pin and a spring-drum, of a sleeve loosely surrounding the pivot-pin and having a horizontal slot, a leaf-spring surrounding the sleeve, a pin projecting from the inner end of the leaf-spring into the slot in the sleeve a lug on the bottom of the sleeve and a stop-lug on the upper surface of the bottom of the drum the outer end of the leaf-spring 60 being held on the drum, substantially as herein shown and described. 65

4. In a spring-hinge, the combination with a pivot-pin of a bracket, a thumb-screw in said bracket for locking the pivot-pin on the bracket, a sleeve mounted loosely on the pivot-pin, a leaf-spring surrounding the sleeve, a spring-drum surrounding the spring, and means for engaging the pivot-pin with the sleeve and the sleeve with the inner end of the spring, substantially as herein shown and described. 70

In testimony that I claim the foregoing as my invention I have signed my name, in presence of two witnesses, this 1st day of 75 May, 1897.

JOHN EDWD. MELLOR.
